UNITED STATES PATENT OFFICE.

WILLIAM KLINE, OF WAYNESBORO, VIRGINIA, ASSIGNOR OF ONE-HALF TO WILLIAM J. MOORE, OF WASHINGTON, DISTRICT OF COLUMBIA.

SOUND-REGULATOR FOR AUDIBLE SIGNALS.

1,342,543.

Specification of Letters Patent.

Patented June 8, 1920.

Application filed February 9, 1918. Serial No. 216,160.

To all whom it may concern:

Be it known that I, WILLIAM KLINE, a citizen of the United States, residing at Waynesboro, in the county of Augusta and 5 State of Virginia, have invented certain new and useful Improvements in Sound-Regulators for Audible Signals, of which the following is a specification.

The present invention relates to improvements in sound regulators for audible signals and particularly constructed and adapted for regulating or modulating the intensity of the sound of a telephone call bell.

15 It is generally the object of my invention to produce a sound regulating device simple in point of construction and operation.

The more particular object is the construction of a device of the character indicated which admits of ready regulation to produce uniform sound effects of desired pitch or quality.

With this end in view, the invention consists principally in the provision of means 25 on a hammer or other element for striking a sound producing device for variously modulating or otherwise differently affecting the sound of the sound producing device.

This and other structural characteristics 30 forming a part of the invention will be hereafter more fully described and particularly pointed out in the appended claims.

In the drawings, in which similar reference characters indicate like parts—

35 Figure 1 is a top plan view of a telephone call bell box with a part of my improvement;

Fig. 2 is a vertical sectional view on line II—II in Fig. 1;

40 Fig. 3 is a vertical sectional view on line III—III in Fig. 2 and

Fig. 4 a perspective view of my invention detached from the surrounding parts.

Referring to Figs. 1, 2 and 3, 10 is the 45 usual call bell box which houses the well-known electro-magnet 11, the specific construction of which is not material for the purposes of my invention.

12, 12 represents the usual form of bells 50 mounted on the top of the box 10. Through a slot 13 in the top of the box extends a hammer centrally located between the bells as is customary. The head 14 of the hammer is provided with a plurality of striking faces 15, 16 and 17 of different tone producing quality. These different faces may

be conveniently formed by boring out portions at diametrically opposite sections of the head 14, and inserting pieces of different material, such as wood, felt, leather, etc. In 60 Fig. 4, the inserts 16 and 17 represent for the sake of illustration, pieces of wood and felt, respectively, while the portion 15 is a metallic surface. While I prefer to form the striking faces in the manner indicated, 65 there is considerable latitude in carrying out the idea involved.

From the head 14 extends a stem 18 downwardly into a sleeve 20 formed to embrace the stem. The sleeve is preferably provided 70 with lateral flanges 21, 21 parallel in proximity to one another, and by means of screws 22 and nuts 23 these flanges may be clamped together to any desired extent, to frictionally embrace and tightly engage the 75 stem 18.

The lower end of the sleeve 20 is designed to receive the stub 24 or lower part of the stem of the usual hammer. By this construction my device can be readily applied 80 to the ordinary structures and arrangements employed by the call boxes of telephone companies. It is merely necessary to cut the stem a short distance above the armature 26 and slip the sleeve 20 over the stub 85 of stem and tighten the screws 22 in the lower portion of sleeve 20. From this construction and arrangement said stem 18 with its head or hammer section 14, not only is pivoted to have a vibratory movement but 90 is also adapted to be rotated through a small angle.

Intermediate its ends the sleeve may be slotted as indicated by the numeral 27, and a block 28 may be inserted in this slot and 95 connected to the stem 18. The block 28 is so shaped that the stem 18 may be turned through a limited angle relatively to the sleeve 20, by the outer projections 25 of block 28 striking against the opposite and 100 outside faces of the lateral flanges 21 adjacent to the slot 27 in the sleeve 20.

From the head 14 extends upwardly a stem portion 30. To this stem portion may be connected by screw threads or otherwise, a 105 knurled head 31 provided with a pointer 32.

A housing 33 of sheet metal or other suitable material is attached to the top of the box 10, as by screws 34. This housing has a slot 35 through which the head 31 passes 110 and on its outer surface the housing carries the indicia S, M, and L, to coöperate with

the pointer 32 to indicate the position of the hammer relatively to the sleeve 20 and thereby the position of the striking surfaces 15, 16 and 17 relatively to the bells 12. A 5 hood 37 is hinged on the housing 33 and has fingers 38 engaging the opposite side of the housing to hold and support the hood in closed position and thereby protect the head 31 and pointer 32 from injury or disturbing 10 their adjusted position.

The operation is obvious. When it is desired to obtain a loud ring, the head 31 is turned until the pointer 32 stands over L. In this position the opposite metallic faces 15 are in striking position adjacent bells 12. By turning the head until the pointer 32 stands over the letter M, the wooden faces 16, are brought into striking position and a medium sound is produced, and when the 20 pointer 32 stands over the letter S, the felt faces 17 strike the bells 12 and a soft sound is produced.

While in the structure described three different striking faces are used, it is obvious 25 that a larger number may be used. Wood, felt and leather are merely referred to as some of the materials available for the purposes of the invention. Other materials may be employed with equally good effect.

30 Numerous changes may be made within the scope of the disclosure. What is shown and described is merely for the purpose of illustrating the broader aspects of the invention.

35 What I claim is:—

1. A sound regulator for audible signals comprising a vibrating sound producing device, a combined pivotally and rotatably mounted stem provided with a hammer having a plurality of striking surfaces of different tone producing quality, means for varying the rotated position of the stem to bring any one of said surfaces of the hammer into striking engagement with the sound 45 producing device.

2. A sound regulator for audible signals comprising a vibrating sound producing device, a combined pivotally and rotatably mounted stem provided with a hammer having a plurality of striking surfaces of different tone producing quality, means at the end of the stem for turning the stem and hammer about its pivot and means adjacent said turning means for indicating the position 50 of the hammer.

3. A sound regulator for audible signals comprising a vibrating sound producing device, a combined pivotally and rotatably mounted stem provided with a hammer having a plurality of striking surfaces of dif- 60

ferent tone producing quality, means at the end of the stem for turning the stem about its pivot, means adjacent said stem for indicating the position of the stem and hammer and means for protecting the said last mentioned parts. 65

4. A sound regulator for audible signals comprising a vibrating sound producing device, a combined pivotally and rotatably mounted stem provided with a hammer having a plurality of striking surfaces of different tone producing quality, means at the end of the stem for turning the stem about its pivot, a pointer adjacent said turning means, an indicator plate supported to co-operate with the pointer to indicate the position of the stem and hammer and a removable hood for protecting all said last mentioned parts. 70 75

5. A sound regulator for audible signals comprising a vibrating sound producing device, a relatively short stub, means for vibrating said stub, a stem, a hammer having a plurality of striking faces of different tone producing quality fixed to said stem, and means for frictionally uniting the said stub and stem. 80 85

6. A sound regulator for audible signals comprising a vibrating sound producing device, a relatively short stub, means for vibrating said stub, a stem, a hammer having a plurality of striking faces of different tone producing quality fixed to said stem, means for frictionally uniting said stub, and stem, means for turning the stem and hammer 90 95 relatively to said stub, and means for limiting such movement of said stem.

7. A sound regulator for audible signals comprising a vibrating sound producing device, a relatively short stub, means for vibrating said stub, a hammer having a plurality of striking faces of different tone producing quality, a sleeve frictionally embracing the abutting ends of the hammer and the stub, and means for varying the frictional engagement between the sleeve and each of the embraced parts. 100 105

8. A sound regulator for audible signals comprising a vibrating sound producing device, a relatively short stub, means for vibrating said stub, a hammer having a plurality of striking faces of different tone producing quality, a sleeve frictionally embracing the abutting ends of the hammer and the stub, means for turning the hammer relatively to said sleeve, and means on the hammer and the sleeve for limiting the relative movement therebetween. 110 115

In testimony whereof I affix my signature,
WILLIAM KLINE.
